UNITED STATES PATENT OFFICE.

SIEGFRIED SCHLESINGER, OF NEW YORK, N. Y., ASSIGNOR TO THE UNITED STATES METALLIC FURNITURE MANUFACTURING COMPANY, OF SAME PLACE.

DESIGN FOR A BEDSTEAD.

SPECIFICATION forming part of Design No. 24,103, dated March 12, 1895.

Application filed November 13, 1894. Serial No. 528,687. Term of patent 3½ years.

To all whom it may concern:

Be it known that I, SIEGFRIED SCHLESINGER, residing at the city of New York, county and State of New York, have invented a new 5 and useful Design for Bedsteads, of which the following is a specification.

Reference is to be had to the accompanying drawing, illustrating in perspective view, a bedstead embodying my design.

10 The leading feature of my design consists in the contour of the skeleton or open-work panel portion of the bedstead as shown in the headboard or footboard, and comprises a rectangular outer frame portion 1, within which 15 is a portion 2 having a general circular or elliptical contour. Within this part 2 is a rod frame portion having a general diamond shape and comprising four side bars or parts 3, which preferably have a slight inward 20 curve. At the points of junction of the parts of the outer frame 1, and also at points of

junction of the parts 2, 3 with each other and with the outer frame, are rosette or knob-like portions 4, the particular contour of which may vary, or these parts 4 may be omitted, 25 without departing from the main essential feature of the design as a whole, and which comprises the combined effect presented to the eye of the ordinary observer by the frame 1, the circular or elliptical contour of the part 30 2, and the diamond-shaped parts 3 within the latter.

What I claim is—

The design for a bedstead, substantially as herein shown and described. 35

In testimony whereof I affix my signature in the presence of two witnesses.

SIEGFRIED SCHLESINGER.
